HANDLE DEVICE

Frank C. Wallace, Los Angeles, Calif., assignor
to Hollywood Comb Curler, Inc., Los Angeles,
Calif., a corporation of California

Application December 13, 1940, Serial No. 369,917

2 Claims. (CL. 16—111)

My invention relates to handle devices and, among its principal objects, I aim to provide a handle or knob which may be easily and securely mounted on a door or the like without the use of bolts or screws; which may be economically made and assembled; which, when once mounted, remains in the installed position without the necessity of subsequent adjustment; and which is strong and durable.

All the above-mentioned features and objects of my invention, as well as other aspects and details thereof, will be best understood from the following description of typical and illustrative forms; although I wish it understood that I do not limit my invention to the details and forms hereinafter illustrated and described since, within the broader scope of my invention as defined by the appended claims, various modifications and adaptations may be made. For purposes of description, reference is had to the accompanying drawing, in which:

Fig. 1 is a side view partly in section and partly in elevation, showing one end of the device in fully mounted position and the other end in partially mounted position;

Fig. 2 is a section on line 2—2 of Fig. 1;

Fig. 3 is a section on line 3—3 of Fig. 1;

Fig. 4 is a fragmentary view partly in section and partly in elevation of a variational form;

Fig. 5 is a view partly in section and partly in elevation of another variational form;

Fig. 6 is an elevational view of the device of Fig. 5 in assembled form;

Fig. 7 is a section on line 7—7 of Fig. 6;

Fig. 8 is a view partly in elevation and partly in section showing a further variational form of device with the locking member in contracted position; and

Fig. 9 is a view partly in elevation and partly in section of the device of Fig. 8 but showing the locking member in expanded position.

Referring now more particularly to the drawing, I show at 5 a section of a wooden base which may be typical of a door or drawer or the like upon which my improved handle is mounted, into which base I first provide a pair of spaced holes 6.

My handle device is comprised of a main body portion having a medial handle 10 and integrally formed ends 11, 11a. Each of the ends is substantially L-shaped, presenting a bottom portion 12 which rests against the base 5 upon which the device is mounted, and a top portion which terminates below the plane of the handle member 10 whereby to provide a shoulder 15 which is

transversely grooved at 16 for the purpose to be described. A hole 20 is provided through each of the bottom elements 12 and mounted in this hole is a tubular insert or locking member preferably made of flexible metal and having a body 22 and prongs 23 presenting sharp end portions 24 for penetrating the side walls of the hole 6. While any desired number of prongs 23 may be utilized, I preferably utilize two pairs of oppositely disposed prongs, the prongs of one pair being relatively longer than the prongs of the other pair. For the purpose of holding the handle in position secured to the base 5, the top end of the insert 22 is provided with an outwardly disposed annular flange 25 which is countersunk into the top face of the end 12 by means of recess 26 in the latter. This flange 25 prevents further downward longitudinal movement of the insert with respect to the hole 20 so that when the prongs 23 are expanded to engage the side walls of the hole 6 in the manner to be herein-after explained, the handle device is securely held onto the base 5. The prongs 23, before being expanded, occupy the contracted position shown 25 at the right-hand end of Fig. 1. I provide two end pieces 30, 30a which fit over the end portions 11, 11a, respectively, each of the said end pieces presenting a longitudinal recess 31 into which fits the outer face and side walls of the respective end portions 11, 11a. A downwardly extending tongue 34 provided in the top of the recess 31 projects into the groove 16 to hold the top end of the respective end members 30 onto the body. At the bottom of each of the end members 30, 35 30a there is a downwardly projecting pin 35 preferably formed as an integral part of the respective end members. This pin is inserted in the tubular insert 22 and when pushed completely down to the point at which the shoulder portion 40 37 abuts the top face of a bottom member 12, 12a, the lower end of the pin enters between and acts to expand the prongs 23 to force their sharp ends 45 24 into the side walls of the hole 6 (see the left-hand end of Fig. 1). In Fig. 1, the right-hand end member 30a is shown in position ready for its pin 35 to be pushed down into the insert 22 to expand the prongs 23, and the left-hand end member is shown in the lowermost or expanding position—that is, the position which the device 50 occupies when fully mounted.

While any suitable material may be used for forming the elements of my device, I have found it particularly suitable to use a plastic in the making of the portions 10, 11, 11a, 12, 30, 30a and 35.

In Fig. 4, I show a slightly modified form of

my device which is identical with the device of Figs. 1 to 3, inclusive, except that the weight of the end members 40 is reduced by the provision of an annular recess 41 around pin 35. The other elements of Fig. 4 are the same as in Fig. 1 and are given like numerals.

In Figs. 5, 6 and 7, I illustrate still another variational form which my invention may take. Referring to those figures, I show a knob comprised of a lower portion 50 having a hollow interior and an opening 51 through its bottom end to receive the tubular insert or locking member 22, which locking member is provided with the prongs 23 as before described. The upper end 54 of the hollow interior is of relatively greater diameter than the lower portion whereby to receive with a snug fit the bottom circular projection 55 of the upper knob portion 57. Depending from the bottom of top knob portion 57 and projecting into the insert 22, I provide a pin 58 which acts to expand the prongs 23 in the manner before described.

From the foregoing description it will be seen that in order to install one of my improved handles or knobs on a door or the like it is only necessary to provide a hole partway through the door or the like large enough to receive the tubular insert, after which the insert portion projecting from the bottom of the handle device is inserted in the hole and the end pieces 30, 30a of Figs. 1 to 3, inclusive, or 40 of Fig. 4 or the top knob portion 57 of Figs. 5 to 7, inclusive, may be mounted by inserting the expanding pin in the insert member to expand the prongs into the side walls of the hole 6. When thus installed, the device is held in position by virtue of the prongs and the flange 25.

In Figs. 8 and 9, I show a further variational form of my invention, and referring to those figures the lower part of the knob member 50 has the opening 51 through its bottom, in which opening is carried a tubular insert 60 which projects into the hole 6 in base 5 and has a pair of oppositely disposed openings 61 in its side wall adjacent its lower end. An annular flange 25 at its top is provided for the purpose before described. The top or movable handle portion corresponding to handle portion 57 in Fig. 5, for instance, carries at its lower end a pin 65 to which a flexible prong member 70 is secured at

66 as by extending through a transverse hole (not shown) in the lower end of pin 65, the ends of the member 70 projecting through opening 61 so that when the device is moved from the contracted position shown in Fig. 8 to the expanded position shown in Fig. 9, the prongs 70 are forced outwardly into the side walls of hole 6. This expanding operation is accomplished by pushing the pin 65 downwardly in the insert 10 from the position of Fig. 8 to the position of Fig. 9.

While I have resorted to considerable detail for the purpose of making my invention understood, I wish it understood that within the broader scope of my invention, as defined by the appended claims, various modifications and adaptations may be made without departing from the spirit of the invention.

I claim:

20. A device of the class described comprising a body presenting a medial handle portion and oppositely disposed L-shaped end portions, a hole through the body of each of said end portions, a tubular locking member mounted in each of 25 said holes, each of said locking members having an outwardly flanged top portion engaging the body and oppositely disposed prongs projecting below the body, and a pair of detachable end portions mounted on said L-shaped end portions 30 of the body, each of said detachable end portions having a portion projecting into each of the respective locking members between said prongs whereby to expand said prongs outwardly.

35. A device of the class described comprising a body presenting a medial handle portion and oppositely disposed L-shaped end portions, a hole through the body of each of said end portions, a tubular locking member mounted in each of said 40 holes, each of said locking members having an outwardly flanged top portion engaging the body and oppositely disposed prongs projecting below the body, a pair of detachable end portions mounted on said L-shaped end portions of the body, each of said detachable end portions 45 having a portion projecting into each of the respective locking members between said prongs whereby to expand said prongs outwardly, and tongue and groove means for securing the said detachable end portions to the body.

FRANK C. WALLACE.
